UNITED STATES PATENT OFFICE.

MARION D. BOLAND, OF APPLETON, ARKANSAS.

COTTON-CHOPPER.

1,387,344.

Specification of Letters Patent. Patented Aug. 9, 1921.

Application filed August 24, 1920. Serial No. 405,563.

To all whom it may concern:

Be it known that I, MARION D. BOLAND, a citizen of the United States, residing at Appleton, in the county of Pope and State of 5 Arkansas, have invented new and useful Improvements in Cotton-Choppers, of which the following is a specification.

The object of my present invention is the provision of a wheeled cotton chopper that 10 is simple and inexpensive in construction, highly efficient in operation, and well adapted to withstand the usage to which cotton choppers are ordinarily subjected.

Other objects and advantages of the invention will be fully understood from the following description and claims when the same are read in connection with the drawings accompanying and forming a part of this specification, in which:—

20 Figure 1 is a top plan view of a cotton chopper constructed in accordance with my invention.

Fig. 2 is a side elevation of the same.

Fig. 3 is a transverse section of the chopper.

Figs. 4, 5, 6, 7 and 8 are views illustrative of details hereinafter specifically referred to.

Similar numerals of reference designate corresponding parts in all of the views of 30 the drawings.

In the present and preferred embodiment of my invention the ground wheels 1 are carried by axle sections 2 and 3. The section 2 is solid, and the section 3 is tubular 35 so as to telescopically receive the section 2.

The said sections are adjustably connected together as indicated by 4 in Fig. 4 so that the ground wheels 1 may be positioned at various distances apart to suit different conditions.

Supported upon the axle sections in such manner as not to interfere with the adjustment thereof is a transverse frame member 5 of inverted U-shape. In addition to the 45 frame member 5 at the rear of the chopper, the frame comprises a forward transverse rectangular frame member 6, upper side bars 7 fixed to the frame members 5 and 6, and a lower longitudinal-central bar 7' connected at its forward end with the lower portion of the frame 6 and at its rear end with one of the frame members 5, being journaled in a hanger 7^x on a transverse sleeve 7^w carried by said frame member 5 50 and mounted on the axle section 3.

A tongue 8 is fixed to the upper portions of the frame members 5 and 6 and is extended forwardly from the latter for the connection of draft animals.

Fixed to the axle sections 2 and 3 is a gear 60 9, and journaled at its opposite ends in bearings on the sleeve 7^w and the forward frame member is a longitudinal shaft 10. The said shaft 10 is provided with a gear 11 that is intermeshed with the gear 9. The 65 ground wheels 1 are provided with peripheral lugs 12 in order to enable the same to positively engage the ground, and by reason of the driving connection described it will be understood that when the chopper is 70 drawn across a field the shaft 10 will be continuously rotated about its axis. The forward portion of the shaft 10 is equipped with sprocket gears 13 and 14, and pivotally and adjustably mounted on the said 75 shaft 10 between the gears 13 and 14 are arms 15 in the outer portions of which are mounted revoluble choppers 16. On the shafts of the choppers 16 are sprocket gears 17 and 18 which are connected through the medium 80 of sprocket belts 19 and 20 with the spur gears 13 and 14, respectively. From this it follows that the rotation of the longitudinal shaft 10 as before described will be attended by rotation of the choppers about their 85 axes. It also follows from the adjustable connection of the arms 15 to the longitudinal shaft 10 that the revoluble cotton choppers 16 may be positioned at various distances apart according to the width of the 90 space between the rows to be operated on.

Adjustably mounted on the side bars of the chopper frame are levers 21 through the medium of which the driver on the seat 22 is enabled to raise either of the choppers when 95 occasion demands. The forward and lower arms of the said levers are connected through the medium of pendent bails 23 with the outer portions of the arms 15.

In the practical operation of my novel 100 cotton chopper as thus far described it will be understood that incident to the traverse of a field by the chopper the revoluble choppers 16 will be rotated transversely and consequently will efficiently serve of purpose ascribed to them.

The adjustable connection of the arms 15 to the shaft 10 will be better understood by comparison of Figs. 2, 5 and 6 when it is stated that the arms 15 are longitudinally 110

slotted as indicated by 15^x to receive adjustable sleeves 16^x one to each arm 15, and which adjustable sleeves 16^x are adjustably fixed to their respective arms through the medium of nuts 17^x. The sleeves 16^x serve to receive the shaft 10.

In Fig. 7 I illustrate a construction in which the choppers 16^a are hinged at 17^a and are backed by springs 18^a, this provision being made in order to prevent injury to the chopper blades in the event of the same striking an obstruction in their paths.

Fig. 8 illustrates the manner in which I prefer to connect the ground wheels 12 with the axle sections. In the said connection a ratchet 50 is fixed on the axle section, and the wheel is loosely mounted on said section and is provided with a spring pressed pawl 51^x in engagement with the said ratchet. This provision manifestly enables the axle to turn while the inner ground wheel is at rest as when the machine is being turned.

As shown in Fig. 2 the gear 11 is splined and shiftable longitudinally on the shaft 10; the said gear being provided with a circumferentially grooved portion 50 engaged with a lever 51 having a detent for coöperation with a fixed segmental rack 51. This provision is made in order to enable the driver to start and stop the chopping means at will.

Having described my invention, what I

claim and desire to secure by Letters-Patent, is:—

1. A cotton chopper comprising a frame, a sectional axle connected with the frame and having means to adjustably connect its sections together whereby ground wheels on the axle section may be spaced at different distances apart, a gear fixed to said axle section, a longitudinal central shaft carried by the frame, a gear on the shaft and intermeshed with the first-named gear, sprocket gears fixed on the longitudinal shaft, slotted arms receiving the longitudinal shaft in their slots, sleeves adjustably receiving the longitudinal shaft, nuts on said sleeves to adjustably fix the same to the arms, cotton choppers mounted in the outer portions of the arms and having shafts and sprocket gears thereon, and sprocket belts connecting the sprocket gears on the shaft and the sprocket gears of the cotton choppers.

2. The combination in a cotton chopper of a longitudinal shaft, means carrying said shaft, means to rotate the shaft, cotton choppers arranged at opposite sides of the vertical plane of said shaft and having shafts in parallelism to the first-named shaft, and driving connections between the first-named shaft and the second-named shafts.

In testimony whereof I affix my signature.

MARION D. BOLAND.
